(57) **CLAIM**

The ornamental design for a breast pumps bag, as shown and described.

DESCRIPTION

FIG. 1 is a front perspective view of a breast pumps bag, showing my new design;

FIG. 2 is a rear perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a front perspective view of a mat portion of a breast pumps bag;

FIG. 10 is a rear perspective view of FIG. 9;

FIG. 11 is a front view of FIG. 9;

FIG. 12 is a rear view of FIG. 9;

FIG. 13 is a left side view of FIG. 9;

FIG. 14 is a right side view of FIG. 9;

FIG. 15 is a top view of FIG. 9;

FIG. 16 is a bottom view of FIG. 9;

FIG. 17 shows the breast pumps bag shown in FIG. 1 combined with the mat portion of the breast pumps bag shown in FIG. 9 in an open position; and,

FIG. 18 shows the breast pumps bag shown in FIG. 1 combined with the mat portion of the breast pumps bag shown in FIG. 9 in a closed position.

The broken lines in the drawings illustrate the portions of the breast pumps bag, which form no part of the claimed design.

1 Claim, 18 Drawing Sheets
